C. PAPE

STOCKING PROTECTOR

Filed June 6, 1925

Patented Oct. 27, 1925.

1,559,001

UNITED STATES PATENT OFFICE.

CHARLES PAPE, OF DENVER, COLORADO.

STOCKING PROTECTOR.

Application filed June 6, 1925. Serial No. 35,469.

To all whom it may concern:

Be it known that I, CHARLES PAPE, a citizen of the United States, and a resident of the city and county of Denver, in the State of Colorado, have invented certain new and useful Improvements in Stocking Protectors, of which the following is a specification.

My invention relates to stocking protectors for preventing undue wear of the stocking at the heel during wear.

Shoes are usually provided with lining which is more or less coarse or with an exposed counter. Fabric lining in the shoe abrades the stocking heel and soon renders the stocking unserviceable. The same is true of the exposed counters, which are usually made from fiber or leather, neither of which can be made sufficiently smooth to prevent wear on the fabric of the stockings.

My invention contemplates the provision of a device which may be made and sold independently of the shoe, and which may be inserted in any shoe to present a perfectly smooth and glass like surface which will entirely eliminate wear on the heel of the stocking. It is furthermore the object of my invention to provide such a stocking protector with an edge which cannot wear nor tear the stocking, and which clings to the shoe in such a way that it cannot be displaced during wear.

Having in view these objects and others which will be pointed out in the following description, I will now refer to the drawings, in which—

Figure 1 is a view in perspective of the stocking protector.

Figure 1^a is a perspective view of a modified form of the stocking protector.

Figure 2 is a perspective view of a shoe with a portion of the back part torn away to expose the stocking protector.

Figure 3 is a sectional view of the same shoe with the stocking protector.

Figure 4 is a median vertical section of the stocking protector.

My stocking protector is made by cutting or punching it out of flat sheet metal, and then bending it before use into the form shown in Figure 1. It has in general the outline of the counter of the shoe. Its lower edge 10 is adapted to rest on the heel of the shoe. The ears 11 are integral with the main portion of the stocking protector, their purpose being to secure the stocking pro-

tector in the shoe and to prevent slippage during wear. The number of ears 11 will depend very largely on the particular circumstances in each case. In shoes in which there is very little or no tendency toward slippage, only two very short ears may be provided at the ends, and these two ears may be left unbent to be thrust down behind the inner edge of the heel, or they may be omitted altogether. In circumstances demanding slightly greater adhesion, the two end ears are bent inwardly as shown in Figure 2, where they may be tacked on to the heel with a thin layer 12 of leather or fabric above to protect the stocking from the edges of the ears. If still greater adhesion is needed, the number of ears similar to the ears 11 may be increased to three, four, five, or even more, and I wish it to be distinctly understood that I do not desire to limit myself to any specified number. I wish it to be also understood that the ears may be continuous with the body of the stocking protector to serve as prongs for engaging the heel of the shoe, or they be bent at an angle to the body of the stocking protector to rest on the heel of the shoe.

The edge 13 of the stocking protector is slightly rounded for two reasons. When putting on or taking off the shoe, the stocking at the heel slides over the rounded surface of the stocking protector and does not come into contact with a possible rough exposed edge. Because it is rounded, the entire edge 13 bears against the inner rear surface of the shoe to hold the stocking protector in a fixed position within the shoe. At 13^a the edge 13 is slightly indented, so that the portions of the edge 13 at each side of the indentation 13^a will bite into the counter or the lining of the shoe to still further hold the stocking protector in place. The indentation 13^a has a further great advantage in that it provides a most suitable edge for the heel of the stocking and foot to slide over when putting on the shoe.

While any suitable material may be used in making the stocking protector, the best results can be obtained only by using materials having certain characteristics. The material must be noncorrodible. It must be capable of receiving an exceedingly smooth or glassy inner surface, by polishing or otherwise, since the stocking protector has its maximum efficiency only when the inner surface is as frictionless as possible.

I have found that there are several metals of very low cost which are admirably adapted for this purpose. Aluminum which is treated so that it will not turn black nor tarnish is well suited for my purpose, since it is relatively inexpensive, is adapted to receive a high polish, and possesses a certain degree of resiliency. Monel metal is another metal which will not rust or turn black and I have found this metal very satisfactory in the manufacture of the stocking protectors. Silver and gold are of course the ideal metals of this purpose when cost is a secondary consideration, since they possess all of the necessary qualities to an extraordinary degree. Of the materials other than metal, bakelite laminated material serves the purpose admirably. Perhaps the best results can be obtained at the lowest cost by making the stocking protectors out of spring steel or similar material and then electroplating their inner surfaces with nickel, silver, or gold. I do not desire, however, to restrict myself to the use of any particular material, but I reserve to myself the right to use any metal which is suitable for the purpose.

While the inner surface of the stocking protector must be as smooth as it is possible to make it, it is desirable and often necessary that the rear surface of the stocking protector be rough. The rear surface is in contact with the inner surface of the shoe, and every means possible must be provided for preventing slippage of the stocking protector in the shoe. The rear surface of the metal may be specially roughened to give it an exceedingly coarse and rough surface, or it may simply be left unfinished. The degree of roughness necessary is of course largely dependent on individual circumstances. The roughened surface may also be applied to a layer 14 of metal, paper, or fabric which is caused to adhere permanently to the rear surface of the stocking protector.

It is my object to provide the stocking protectors in a number of different forms and sizes to fit the various kinds and sizes of shoes. The number need, however, not be large since a stocking protector of any given size will fit in shoes of considerable variation in form and size. In storage and

shipment the stocking protectors nest well and occupy very little space. It is a very simple matter to apply them to the shoes. They are resilient and they therefore adapt themselves readily to the form of the shoes. They may be tacked down with a layer of suitable material covering the ears, or the ears may be thrust down behind the insole to anchor the stocking protector in the shoe. The stocking protector is, however, made to cling to the shoe also by means of the rounded outer edge and the roughened rear surface, so that there can be no annoying slippage during wear. During wear and when putting on or taking off the shoes, the stocking slides over a curved and highly glazed surface, so that there is practically no friction contact to wear out the heels of the stockings. I have found that the stocking protectors are especially serviceable when used with silk stockings, as the added wear of the silk stockings will soon pay for the stocking protectors of even the most expensive kinds.

Having thus described my invention in terms which will be readily understood by others skilled in the art to which it pertains, what I claim as new and desire to secure by Letters Patent of the United States is:

A stocking protector which is adapted to be placed inside a shoe against the inner rear surface thereof, said stocking protector being formed out of a sheet of resilient and noncorrodible material and having a highly polished exposed forward surface and also a rear friction surface, the upper and lateral edges being turned rearwardly so that the edges will engage the lining of the shoe and providing also a curved surface for the passage of the heel of the stocking when putting on the shoe, the upper edge of the stocking protector having a reentrant curve to facilitate the passage of the heel of the foot when putting on the shoe and also providing projections on each side of the reentrant curve for digging into the lining of the shoe, and a plurality of ears projecting from the lower edge of said stocking protector, said ears being adapted to secure the stocking protector to the heel of the shoe.

In witness whereof I affix my signature.

CHARLES PAPE.
